GO-CART

Frank Kurtis, Glendale, Calif., assignor to C. E. Erickson
Co., Inc., Des Moines, Iowa, a corporation of Iowa

Filed Jan. 18, 1960, Ser. No. 59,097

Term of patent 14 years

(Cl. D14—3)

FIG. 1

FIG. 2

Fig. 1 is a front perspective view of a go-cart showing my new design; and

Fig. 2 is a rear perspective view.

The dominant features of my design reside in the portions shown by full lines in the drawings.

I claim:

The ornamental design for a go-cart as shown and described.
